(No Model.)

H. E. WERLINE.
INCANDESCENT ELECTRIC LAMP SOCKET.

No. 478,149.

Patented July 5, 1892.

UNITED STATES PATENT OFFICE.

HENRY ELMER WERLINE, OF LANCASTER, ASSIGNOR, BY DIRECT AND MESNE ASSIGNMENTS, TO THE WERLINE ELECTRICAL SPECIALTY COMPANY, OF YORK, PENNSYLVANIA.

INCANDESCENT-ELECTRIC-LAMP SOCKET.

SPECIFICATION forming part of Letters Patent No. 478,149, dated July 5, 1892.

Application filed December 22, 1891. Serial No. 415,896. (No model.)

To all whom it may concern:

Be it known that I, HENRY ELMER WERLINE, a citizen of the United States, residing at Lancaster, in the county of Lancaster and State of Pennsylvania, have invented certain new and useful Improvements in Regulating-Sockets for Incandescent Electric Lamps; and I do hereby declare the following to be a full, clear, and exact description of the invention, such as will enable others skilled in the art to which it appertains to make and use the same.

This invention relates, chiefly, to electric-lamp sockets provided with helical resistances and means for cutting one or more or all of them out of circuit at will to vary the intensity of the light, the same means being also available for breaking the circuit altogether.

The objects of the said invention are to prevent distortion of the said resistances when they are being put into place, to keep them properly insulated and separated, to lessen the cost of manufacture, and to guard against too strong a current, in order that I may use for said resistances carbon in the open air, thereby saving the expense of platinum or a vacuum-chamber.

In the accompanying drawings, Figure 1 represents a vertical section of an electric lamp and socket embodying my invention. Fig. 2 represents a horizontal section through the said socket, taken on a plane above the said resistances. Figs. 3 and 4 represent in side elevation, partly in section, the resistance terminal-plates and the switch controlling them, also the supporting devices for the same; and Fig. 5 represents a side elevation of resistances and their support. Fig. 6 shows the detachable light-regulating device removed from the socket.

In said drawings, A represents the bulb of the lamp, hung downward, as is usual, though of course it may be held upright or in any other position. In this is the usual illuminating-filament a , from which wires or other electric connections a' a^2 extend, respectively, to a central metallic block A' and a metallic shell A^2 , inclosing the neck of the said bulb, the space between the said block and shell

being filled by insulating material a^3 . The 50 said shell is in contact with a metallic sleeve B, the two being preferably screw-threaded and thereby connected together. The said block is in contact with a metallic block or bolt-head B' , this latter part and the said 55 sleeve being attached to a disk C of wood or other insulating material. Two screws c pass through this disk, also passing first through a flange b of the lower end thereof, so as to hold the said sleeve in place. They also make 60 electrical connection between the said sleeve and the horizontal arms d d of the lower end of an upright metallic frame-piece D. This piece is L-shaped in outline, a small horizontal upper flange d' being fastened by a screw e 65 or otherwise to a second disk E, resembling the disk C aforesaid. The screw e or its equivalent, passing through the upper disk E, makes 70 electrical connection between the said metallic frame-piece D and one of the circuit-wires F of the lamp. The other circuit-wire F' is connected by a screw e' , passing through the said disk E, with a bent plate G, the vertical arm of which is fastened by a screw g to an upright bar H of wood or other insulating 75 material extending from one disk to the other. This bar is fastened at its lower end to the disk C by means of an angular plate h , which is attached to the said bar by a screw h' and to said disk by a screw b' , formed with 80 the block or bolt-head B' aforesaid. The said disks, with the frame-piece D and wooden bar H, constitute the frame of the socket. On this frame an outer shell or casing of sheet metal is fitted, consisting of a cylindrical body 85 I and end cap J.

The screw h' holds to the wooden bar H a light metallic arm K, which is curved to fit the cylindrical shape of the socket. A similar arm L is attached to the said wooden bar 90 near the middle of the latter by a screw l , which makes connection with a plate M on the front of the said bar. A short wire k of fusible material extends from one of these arms to the other. The middle part of bar H 95 is enlarged to form a disk H' , on which are fastened the said plate M and four or more additional plates $M' M^2 M^3 M^4$, which are in-

sulated from each other and arranged in a circle. A switch or regulating-button N, the inner part only of which is of electrically-conducting material, is provided with a flat 5 metallic finger N', whereby it makes contact with one or another of the said plates, according to the position into which the said switch and finger are turned. The inner end of the said switch extends through the said disk H', 10 formed on the bar H, and is provided with a transverse pin n, that makes contact with the lower end of a spring-plate G', which is formed from the vertical arm of the plate G aforesaid. The lower end of this spring-arm has an opening g', which allows the end of the switch to 15 pass through it. After the pin n is put in place the spring-plate G' bears inwardly against it, so as to hold the finger N' against one or another of the said plates M M' M² M³ 20 M⁴. The plate M⁴ has no other electrical connection. When the said finger n is in contact with it, the circuit is broken. This plate is provided with a stop n', beyond which the 25 said finger cannot pass, to insure immediate circuit-breaking when required, since the switch need only be turned until it can turn no farther.

When the finger N' is in contact with the plate M, the electrical current is at its maximum and the light at its brightest. The circuit is then through line-wire F and screw e 30 to frame-piece D, thence through screws c, sleeve B, shell A², wire a², filament a, wire a', blocks A' and B', and screw b' to the plate h, 35 thence through arm K, fusible wire k, arm L, and screw l to the plate M, thence through finger N' and the metallic inner part of the switch N to the spring-plate G' and the plate G, thence through the screw e' and the line- 40 wire F' to the generator and intermediate devices, (not shown,) completing the circuit.

To provide for varying degrees of light, I employ a series of helical resistances O O' O², 45 of carbon, the lower end of resistance O being connected by a wire P with a plate P', which is connected by a screw p with the plate M. The other end of resistance O is connected by a wire P² with the lower end of resistance O', and from the middle of this wire a wire 50 p' extends to a plate P³, connected by a screw p² with the plate M'. The upper end of resistance O' is similarly connected with the lower end of resistance O² by a wire Q, from the middle part of which a wire q extends to 55 a plate q', connected by a screw q² to the plate M². From the upper end of the resistance O² a wire r extends to a plate r', connected by a screw r² with the plate M³. Of course the number of resistances may be 60 varied; but for practical purposes three will suffice. The system of attachment and arrangement will be the same whatever the number.

The plates P', P³, q', and r' are attached to 65 the wooden bar H, but easily disconnected by removing the fastening-screws. It is best,

however, to keep these parts together, the said wooden bar and all its attachments, including the resistances, being easily inserted in the socket, using the outer non-conducting 70 part of the switch as a handle. For such attachment or the corresponding detachment it is necessary only to insert or withdraw the screws e b', that fasten the disks G E to the plates G and h, attached to the said bar. 75 When this latter is out of place, the frame-piece D holds the said disks in position together. The wires P, P², p', Q, q, and r stiffen the resistances and tend to make them retain their positions as a whole. To make 80 this much more effective, the horizontal parallel wires P, p', q, and r are made to pass through a transverse rigid supporting bar or stay R, preferably of glass, fused thereon. This prevents twisting and distortion of the 85 resistances while these are being introduced into the socket or withdrawn therefrom and gives strength and fixity of form to the resistance series as a whole. The said resistances are preferably of very light porous carbon filaments having a high specific resistance as compared with electric-lamp filaments, and at the same time allowing a sufficiently 90 large cross-section to resist ordinary mechanical injury. By reason of the low temperature due this method of construction the said resistances may be used in open air, thus reducing the size of the socket by doing away with all need for a vacuum-chamber. The 95 cost is also greatly reduced, especially as there 100 is no need for a platinum seal.

The fusible wire k, already described, affords an effectual guard against injury to the resistances by excessive current passing through them, as such excess will melt the 105 said wire before it can injure the resistance-carbon. This fusible wire may be protected from the radiant heat of the resistance by a shield of mica or other non-conducting and incombustible material. When the light is 110 to be turned down, the switch is turned so that the finger N' will pass from plate M to plate M', M², or M³. In the first case the resistance P is introduced into the circuit with its connecting wires and plate, in the second 115 the two resistances P and P', in the third the three resistances P, P', and P², the resistance and consequent diminishing of the light proportionately increasing. The circuit 120 in other respects remains the same as hereinbefore described. By turning the finger N' to the plate M⁴ the light is extinguished altogether.

The cap-piece J is provided with a tapering tubular extension J', having an opening J² in its side, so that the wires F F', which are suitably covered and twisted together, may be drawn through this aperture, if desired, as shown. Such a construction is very convenient when the lamp and socket are to 125 be attached to a gas-fixture or other structure compelling the conductors to run outside 130

of it and will avoid the mutilation of the socket-casing which in such circumstances would otherwise be necessary.

Having thus described my invention, what I claim as new, and desire to secure by Letters Patent, is—

1. A light-regulating device for electric lamps, consisting of a switch and connecting-plates, in combination with a series of resistances which are connected together and severally connected to the said plates and a rigid supporting bar or brace H within the lamp-socket, through which the terminals of the said resistances pass, the said bar not

forming part of any inclosure, but being a simple supporting and bracing device for the said resistances, substantially as set forth.

2. In an electric-lamp socket, a series of connected resistances composed of carbon filaments and connecting-springs, the latter serving to give stiffness, substantially as described.

In testimony whereof I affix my signature in presence of two witnesses.

HENRY ELMER WERLINE.
